UNITED STATES PATENT OFFICE

HARRIS B. HOLT, OF DORMONT, PENNSYLVANIA, ASSIGNOR TO ROSEDALE FOUNDRY & MACHINE COMPANY, A CORPORATION OF PENNSYLVANIA

CHAIN GRATE

Refiled for abandoned application Serial No. 364,096, filed May 18, 1929, and in Canada January 22, 1931.
This application filed May 5, 1932. Serial No. 609,544.

This invention relates to improvements in chain-grates such as are commonly employed in the furnaces of power plants and other like places, and consists in such an organization of the chain-grate as to provide for the discharge of ashes at the front of the furnace; that is to say, at that end of the furnace, ordinarily the accessible end, at which the fuel is introduced.

10 The invention is illustrated in the accompanying drawings. Figure I is a view in longitudinal section of a furnace equipped with the chain-grate of my invention; Figure II is a view in side elevation of a single link 15 of the chain-grate of the particular form which I prefer to employ; Figure III is a view in plan of the link articulated in its place in the grate structure; Figure IV is a fragmentary view in vertical section of the 20 rear portion of the grate in assembly with a certain block with which the grate there cooperates; Figure V is a view similar to Figure IV, illustrating a modification and an elaboration in detail.

25 The endless, travelling grate 1, borne on a sprocket roller 2 and a smooth roller 3, is disposed in upper and lower reaches 1a and 1b, respectively, as is shown in Figure I. As seen in Figure I, the direction of travel of the upper reach of the chain-grate is from 30 left to right, and the direction of the lower return reach is from right to left. As is here shown and ordinarily would be the case, the two reaches extend in substantially horizontal position. At the front of the furnace—the left-hand end, as seen in Figure I—the grate extends beyond the furnace, and above this extension a coal chute 4 is shown to be arranged. This chute is accessible to 40 receive its charge, and the chute is so arranged as to deliver upon the advancing grate a layer of fuel of desired depth. This layer of fuel the grate carries from left to right, into and through the furnace chamber. In its 45 progress through the furnace chamber the fuel is burned; and at the right-hand end of the structure the grate, rounding roller 3, carries the ashes downwardly. It is common to have an ash pit at this remote end of the 50 structure, the right-hand end as seen in Fig-

ure I. My invention consists in such a particular structure and co-operation of parts as will effect the carrying of the ash by the travelling grate from the remote end of the structure forward again in right-to-left direction to the front of the furnace and the delivery of the ashes to an ash pit 5, situated there.

55 Referring to Figures II, III and IV, the grate will be seen to be made up of links 11 of elongate form provided with terminal eyes 12 through which eyes rods 13 may be threaded in usual manner to form the articulated structure. Preferably, as shown in Fig. III, the fuel-sustaining portions 14 of the links 60 are double the width of the portions which are perforated with the eyes 12, and the links are assembled upon the rods 13 in the usual echelon formation, indicated in Fig. IV. The fuel-supporting face of each link is made up 65 of a plurality of imperforate areas: an area 14 extends in parallelism with the plane of advance; an area 15 anterior to area 14 is forwardly concave and meets area 14 perpendicularly, at the angle α , as shown in Fig. II; a 70 third area 16 is rearwardly inclined from area 14. In consequence of the particular formation of the link, the assembled grate, as is best illustrated in Fig. IV, has a fuel-supporting surface the plane of whose continuity is interrupted with pockets 17. These 75 pockets are so particularly shaped and disposed that they carry forward material resting in them, and, when it comes to the delivery of the ashes, these pockets, co-operating with the parts presently to be described, drag the ashes in the direction of the advance 80 of the grate over a co-operating surface. The widened fuel-supporting faces of the link are minutely shaped to facilitate the passage of streams of combustion-sustaining air through 85 the grate and between the links, but with this matter of aeration of fuel the present invention is not immediately concerned. So far as concerns the supporting of the fuel, the upper surface of the grate, throughout its upper reach, affords substantially continuous support.

90 Means are provided to co-operate with the 95 endless travelling grate throughout its re- 100

turn reach, and to carry the ashes to a point of discharge at the front of the furnace. These means include a block 6 arranged adjacent the smooth roller 3 and having a surface 5 curved to parallelism with the grate as it rounds the roller 3, and against which the ashes borne by the grate are pressed as the grate advances. From the lower end of the block 6 and in parallelism with the lower 10 reach of the grate a plate 7 extends forwardly to the ash pit 5.

As the travelling grate rounds the roller 3 with a burden of ashes resting largely in the pockets 17, this burden is shifted to bear 15 upon the rounded face of block 6, and then in turn to bear upon the plane surface of plate 7. The block 6 and the plate 7 are so spaced from the travelling grate that the recessed grate engaging the ashes shall drag 20 them over the surface of these parts to the forward end of plate 7, where the ashes fall freely into the pit 5.

The rounded surface of the block 6 is preferably provided with ribs 61 extending in 25 the direction of grate travel. Such ribs are effective to cause the travelling grate to exert upon the burden of ashes strains, such as to effect the crushing of lumps of clinker and the like.

80 In operation the travelling grate carries fuel from chute 4 in the manner described through the burning region within the furnace, and from the burning region it carries the ashes into the run-way defined by and between its own body and the surfaces of block 35 6 and of plate 7. By virtue of its pocketed formation, the grate drags the body of ashes in more or less segregated masses through this run-way and delivers them to the pit 5. 40 As it so operates, it effects crushing of clinkers and larger lumps, this crushing operation being generally accomplished between the grate structure itself and the face of block 6.

45 An elaboration of the means for crushing lumps of ash and clinkers, which may be preferred in the use of coals of certain grades and qualities, is shown in Fig. V, where in the face of the block 6 an idly turning corrugated roller 62 is set. With this roller the travelling grate co-operates more certainly to accomplish the crushing described. It will be observed that, regarding the grate as a dragging member, for dragging the ashes 50 over plate 7, each pocket has a posterior wall, concave to the direction of progress, which meets the plane of plate 7 perpendicularly, as shown in Fig. IV. This application is a substitute for my application for "chain grate", filed May 18, 1929, Serial No. 364,096.

I claim as my invention:

1. A furnace structure including an endless chain grate arranged in upper and lower 65 reaches and a drag plate underlying the

lower reach of the grate, the grate surface affording substantially continuous support for fuel and being provided with pockets each of which extends transversely and in continuity throughout the width of the 70 grate, the pocket-wall on the leading side being inclined at a smaller angle to the general plane of the grate surface, and the pocket-wall on the following side being inclined at a larger angle to the general plane of the 75 grate surface.

2. A furnace structure including an endless chain grate arranged in upper and lower reaches with rounded communicating ends, and a confining wall for ashes spaced from the grate at the descending rounded end thereof and thence along its lower reach, and forming with the grate a drag-way for ashes, such wall opposite the rounded end of the 80 grate being ribbed in the direction of chain 85 travel.

In testimony whereof I have hereunto set my hand.

HARRIS B. HOLT.
